UNITED STATES PATENT OFFICE.

JAKOB CORZILIUS, OF PATERSON, NEW JERSEY.

INDICATING DEVICE FOR LOOMS FOR WEAVING DOUBLE-PILE FABRICS.

SPECIFICATION forming part of Letters Patent No. 658,242, dated September 18, 1900.

Application filed June 1, 1899. Renewed February 3, 1900. Serial No. 3,908. (No model.)

To all whom it may concern:

Be it known that I, JAKOB CORZILIUS, a citizen of Germany, residing at Paterson, in the county of Passaic and State of New Jersey, have invented certain new and useful Improvements in Indicating Devices for Looms for Weaving Double-Pile Fabrics, of which the following is a specification.

This invention relates to an indicating device for looms for weaving double-pile fabrics; and the object of the invention is to provide looms with an indicating band or apron which is arranged on a roll back of the printed pile-warp threads as they are led off from their beam, said indicating band bearing colors which match with the colors of the said pile-warp threads or yarn and enable the weaver to ascertain exactly what colors are being woven into the fabric.

The invention consists of certain features of construction and combinations of parts to be hereinafter described and then claimed.

In the accompanying drawings, Figure 1 is a side elevation of my improved loom, partly in section; and Fig. 2 is a sectional elevation on line 2 2 of Fig. 1.

Similar letters of reference indicate corresponding parts.

Referring to the drawings, A indicates the loom-frame, B the beams for the linen warps b, and C is the beam for the printed pile-warp C'. The lay D and heddles E are operated in any usual or preferred manner.

Arranged under the guide-rolls C' of the printed pile-warp threads C' or in any other convenient position, so as to be behind the same, is an indicating band or apron F, this band being preferably supported as shown—that is to say, it runs over a supporting-roll G, provided with small teeth for engaging the same and causing it to travel, said roll G being mounted in the frame A and arranged so that the printed pile-warp threads C' are guided and passed over it. Parallel with the roll G there are preferably arranged upon the frame A two guide rolls or bars G' G'', over which the indicating band or apron F is hung, so that it can be moved by hand into the desired position and so that a wide portion f is formed at a point between the rollers

G' G''. The indicating band or apron is caused to travel through the medium of the roll G, which is rotated by the action of a gear-wheel G² or a chain connecting the roll G and the roll C², so that it travels at the same rate of speed as the said printed pile-warp.

The pile-warp threads bear the different colors in the same relation as on the band, and the indicating band or apron is caused to have such relation to the colors of the said warp as that they will match, and it can be ascertained at any time by looking at the portion f of the said indicating band or apron if the warp is printed and beamed correctly or not. It is not possible or feasible for the weaver to ascertain this by looking at the fabric as it is being woven, and for this purpose the said indicating band or apron is provided with the colors or figures which the pile-warp threads bear and are arranged so that the colors of each match at the point where the said pile-warp threads and the indicating band or apron come in contact.

Having thus described my invention, what I claim as new, and desire to secure by Letters Patent, is—

1. In a pile-fabric loom, the combination, of an indicating band or apron having colors matching with the colors of the pile-warp threads, and means for imparting motion to said band or apron simultaneously and at the same rate of speed as the pile-warp threads, substantially as set forth.

2. The combination, in a pile-fabric loom, of an indicating band or apron having colors matching with the colors of the printed pile-warp threads, a supporting-roller and a guide-roller for said band or apron, and means for rotating said supporting-roller through the medium of said pile-warp threads, substantially as set forth.

In testimony that I claim the foregoing as my invention I have signed my name in presence of two subscribing witnesses.

JAKOB CORZILIUS.
